Geo. Kimmel.
ATTORNEY.

UNITED STATES PATENT OFFICE.

JAAKKO WEHKAOJA, OF ROYALSTON, MASSACHUSETTS.

TOY.

Application filed July 21, 1923. Serial No. 652,948.

To all whom it may concern:

Be it known that I, JAAKKO WEHKAOJA, a citizen of Finland, residing at Royalston, in the county of Worcester and State of 5 Massachusetts, have invented certain new and useful Improvements in Toys, of which the following is a specification.

This invention relates to toys, of the figured type and embodies a toy representing 10 a miniature horse-drawn sled.

The invention comprises a sled provided with a low sided seat thereon and having at the front end a linked connection with a pair of runners which support a toy horse.

15 Provision is made for attaching to the runners of the sled and those supporting the horse, sets of wheels to convert the device into a wheeled toy.

It is of course understood that the size 20 of this toy may be materially increased so that it will support a child.

It will be seen that a toy is obtained from which a child may derive a great deal of pleasure, and that it is simple in construction 25 and may be light in weight yet strong and durable, as it is evident that it may be constructed of wood or metal or both, according to the size in which it is made.

The invention will be best understood 30 from a consideration of the following detailed description taken in connection with the accompanying drawing forming a part of this specification, with the understanding that the invention is not confined to any 35 strict conformity with the showing of the drawings, but may be changed and modified, so long as such changes and modifications mark no material departure from the salient features of the invention as expressed in the 40 appended claims.

In the drawing:—

Fig. 1 is a side elevation of the device embodying this invention.

Fig. 2 is a top plan view of the same, the 45 horse being removed, and

Fig. 3 is a detail of the forward runners, showing in dotted lines the application of wheels thereto.

Referring now to the drawings in detail,

wherein like numerals of reference indicate 50 corresponding parts throughout the several views of the drawing, 1 indicates a sled body supported by a pair of runners 2—2 through the medium of connecting members 3. While the drawing shows these three parts integral it is understood that a different method of construction may be employed.

Upon the top of the body at the rear thereof there is provided a passenger seat 4, having a low back 5 and sides 6 as shown. 60 Forward of the seat there is positioned a driver's seat 7.

The forward part of the body 1 is finished off in a round point as at 8 and has an aperture therethrough.

65 Positioned forwardly of the sled just described, is a second pair of runners 9—9, having at their central parts an integral, inverted, substantially U-shaped portion comprising uprights 10, and a cross connecting member 11, the member 11 having an aperture through its central part. A link member 12, having an aperture through each of its ends connects the sled and runners together by means of bolts 13—13.

70 A figure of a horse 14, is mounted upon the runners 9, over the members 11 and 12.

Upon each of the runners 2—2 and 9—9 there is formed at the front and rear upright oppositely disposed ears 15, having passages 80 16 therethrough providing axle boxes for the reception of the ends of axles 17, upon which wheels 18, may be placed when it is desired to transform the sled into a wheeled toy.

Having thus described the invention, what 85 is claimed as new is:—

1. A toy representation of a horse drawn sled comprising a front and rear pair of sled runners, each runner having thereon means to provide an axle box, a body supported by and formed integral with one of said pair of runners, a passenger seat thereon, a driver's seat thereon, a representation of a horse on said front pair of runners, and a link connection between the front pair 90 of runners and said body.

2. A toy representing a horse drawn sled comprising a front and rear pair of

sled runners, each runner having thereon up-standing apertured ears to provide axle boxes, a body supported above and integral with said rear pair of runners, a passenger seat thereon, a driver's seat thereon, an inverted substantially U-shaped cross member connecting said front pair of runners, a link

between said cross member and said body, and a representation of a horse upon said front pair of runners. 10

In testimony whereof, I affix my signature hereto.

JAAKKO WEHKAOJA.
